METHOD OF MAKING PIPE BENDS

James Hall Taylor, Oak Park, Ill., assignor to
 Taylor Forge & Pipe Works, Cicero, Ill., a corporation of Illinois

Application June 1, 1931, Serial No. 541,337

7 Claims. (Cl. 29—157)

My invention relates to a method of making pipe bends or elbows.

Its object is to effect the manufacture of pipe bends or elbows from sheet metal.

5 My method is illustrated, by example, in the accompanying drawings in which Figures 1 to 11, inclusive, illustrate successive steps and Figure 12 illustrates the final step and the finished article; Figures 9A, 10A and 11A illustrate successive steps of a modification.

Figure 1 illustrates a pair of blanking dies, *a*, *b*, the former being in the form of an annulus and the latter being in the form of a fitted plunger to operate therein. These dies stamp 15 circular blanks, indicated in dot-and-dash lines at *c*, from the sheet stock *d*.

Figure 2 illustrates a pair of cupping dies *e*, *f*, the former being in the form of an annulus and the latter being in the form of a plunger 20 operating in the former, spaced therefrom by the thickness of the stock. Annular die *e* is provided with a guide *g* in the form of a ring disposed, as shown, slightly eccentric to the opening in the die. The ring *g* is of such size 25 as to receive the blank *c* and when the plunger *f* descends into the annulus *e* the blank is cupped, as shown, the rim on one side being deeper than that on the other because of the eccentricity referred to. The blank is conveniently 30 pushed through the annular die in this operation.

Figure 3 shows the next pair of dies, *h* and *i*, again an annulus and a plunger, respectively, which receive the blank from the dies of Figure 35 2, as indicated in dot-and-dash lines. The dies *h* and *i* have a secondary cupping action, whereby the blank is deeply dished into a frustrated dome shape. In this instance, the blank must be removed upwardly after the operation and 40 suitable ejector mechanism may be provided.

Figure 4 illustrates the next pair of dies, *j* and *k*, again an annulus and a plunger, respectively. The blank from the dies of Figure 3 is placed on the annular die *j*, as indicated in 45 dot-and-dash lines, and the descent of the plunger *h* results in a further deepening of the blank and a reduction in diameter to a thimble shape. In this instance, also, the blank must be removed upwardly after the operation and 50 suitable ejector mechanism may be provided.

At this stage in the process the blank has reached the form shown in Figures 5 and 6, the latter figure being a horizontal sectional view taken on the plane of the line 6—6 of Figure 5.

55 The blank, at this stage, is then to be flattened

somewhat, i. e. reformed to a shape of more or less oval cross-section, and may also be bowed over slightly, as will be seen. These steps may conveniently be accomplished in one operation by forming it over a horn die *m*, Figure 7, co-operating with an annular die *l*. After this operation, the blank has the vertical section shown in Figure 7 and the cross-section of Figure 8 which is taken on the plane of the line 8—8 of Figure 7. The vertical section is of more or less parabolic form with an offset focus, the deeper side of the blank being bowed over more than the shallow side, and the cross-section is a somewhat flattened one, as shown. Suitable ejector mechanism may be provided for the dies 60 of Figure 7.

The above description with reference to Figures 1 to 8 is merely illustrative of one method of producing a cup-shaped blank with facility and expedition, and is not essential to the method of my invention. In fact, it is not necessary that the blank be of cup-shape, and a flat blank 75 may be utilized if desired, as will later appear. My invention resides more particularly in the production of a pipe bend, or analogous curved 80 article, by forcing a suitable blank through the opening of a closed circular exterior die by means of a curved interior die bearing at its end on the blank, the dies having relative arcuate movement and the blank being shrunk onto and 85 drawn over the interior die to conform thereto.

When the blank has reached the stage illustrated in Figures 7 and 8, it is then subjected to the action of further dies which are capable of angular as well as straight line movement relative to each other. These dies are shown in Figures 9, 10, and 11. They comprise the ring die *o*, with a flared opening *p*, and a horn die *q* for operation therein. The blank from the dies of Figure 7 is disposed upon the ring die *o*, as 90 shown in Figure 9, with the horn die *q* projecting into the blank, the end of the horn die *q* being then concentric with the opening in the ring die *o*.

As illustrated in Figure 10, a plunger *r* descends upon the horn die *q* and brings it down so that its end engages within the ring die *o*. This action may, if desired, give final form to the short side of the blank, i. e. the inner side of the ultimate bend, alone, by engaging it between ring die *o* and the horn die *q*, the flare of the opening in the ring die and the horn die being shaped accordingly, i. e. the flare is made to the finished curve of the inner side of the article. This action also begins the final forma- 100 105 110

tion of the elbow throughout its circumference, as shown, on the plane of the dot-and-dash line $x-x$. After the operation illustrated in Figure 10, the horn die q is swung through 90 degrees, about the center x' , lying in the plane $x-x$, to the position shown in Figure 11, the plunger r being raised away when desired. In this operation the horn die q drives the blank through the ring die o to complete the formation 10 of the arcuate surface of the bend or elbow. The horn die is then swung back to its former position and the blank may drop through the ring die o , as is evident from Figure 11.

The closed end of the blank is then cut off and 15 the other end is trimmed, as indicated in Figure 12, the finished article then being as shown in full lines in that figure.

In the modification illustrated in Figures 9A, 10A and 11A, I subject the flat blank c of Figure 1 directly to the action of dies like those of Figures 9, 10 and 11. That is, it is also possible to subject a blank to the ring and arcuate dies without the preliminary cupping. In this modified form the parts o' , q' and r' are analogous to parts o , q and r of Figures 9, 10 and 11. In addition, guide s is provided to locate the blank c appropriately relatively to opening p' , somewhat off center, as illustrated, and fingers t are provided to hold the blank down upon 30 ring die o' . The action is shown in Figures 10A and 11A and after the operation of Figure 11A the operation of Figure 12 results in the finished article.

The above description is specific to embodiments of my process and it is so presented in order to instruct those skilled in the art in the use of my invention. It will be evident, however, that changes and modifications can be made without departing from its teachings and spirit, and the broader scope of my invention must be gauged by the broader of the appended claims.

I claim:

1. The method of making pipe bends, which 45 comprises drawing and shaping a blank over a curved interior die to conform to the latter by inserting said die, with the end thereof in contact with the blank, through an exterior closed circular die in contact for the full circumference of its opening with the blank, by combined rectilineal and arcuate relative movement between the dies.
2. The method of making pipe bends, which 55 comprises shrinking and drawing the blank over an inner curved die to conform to the latter, by forcing it through a relatively restricted cir-

cular opening of an outer closed die in contact for the full circumference of its opening with the blank, by relative rectilineal and arcuate movement between the dies.

3. The method of making pipe bends, which 80 comprises disposing a blank in proximity to a closed circular outer die, forcing the blank into the die opening by relative rectilineal movement between the outer die and a curved inner die having its end in contact with the blank, and then forcing the blank through the outer die by relative arcuate movement between the dies and thereby radially reducing the blank throughout its entire circumference and shaping and drawing the blank over the inner die to conform thereto.

4. The method of making pipe bends, which 85 comprises disposing a blank in proximity to a closed circular die having an opening of less cross-area than the blank, forcing the blank into the die opening by rectilineal movement of a curved inner die having its end bearing on the blank, and then forcing the blank through the outer die by arcuate movement of the inner die thereby shrinking and drawing the blank 90 about said inner die to conform thereto.

5. The method of making pipe bends, which 95 comprises forcing a cup-shaped blank, closed at one end and flaring toward its other end, through an outer closed circular die, by means of an inner curved die with its end in contact with the closed end of the blank and by relative arcuate movement between the dies, thereby shrinking the blank over the inner die to conform thereto.

6. The method of making pipe bends, which 105 comprises forcing a cup-shaped blank, closed at one end and flaring toward its other end, through an outer closed circular die, by means of an inner curved die with its end flat and in a single plane and in contact with the closed end of the blank, and by relative arcuate movement between the dies, thereby shrinking and drawing the blank over the inner die to conform thereto.

7. The method of making pipe bends, which 115 comprises disposing a flat blank in proximity to a closed circular die, and forcing the blank through said die by means of a curved inner die with a flat end disposed in a single plane and seating flatwise against the blank, and by combined rectilineal and arcuate relative movement between the dies, thereby shrinking and drawing the blank over the inner die to conform thereto.

JAMES HALL TAYLOR.
